UNITED STATES PATENT OFFICE

160,482

AUTOMOBILE

Howard A. Darrin, Hollywood, Calif., assignor to
Kaiser-Frazer Corporation, Willow Run, Mich.,
a corporation of Nevada

Application February 21, 1950, Serial No. 8,043

Term of patent 14 years

(Cl. D14—3)

To all whom it may concern:

Be it known that I, Howard A. Darrin, a citizen of the United States of America, residing in Hollywood, in the county of Los Angeles, State of California, have invented a new, original, and ornamental Design for an Automobile, of which the following is a specification, reference being had to the accompanying drawings, forming a part thereof, wherein:

Figure 1 is a perspective view of an automobile, embodying my new design, as viewed from the front right-hand corner thereof;

Fig. 2 is a view similar to Fig. 1, but viewed from the rear right-hand corner thereof;

Fig. 3 is a front elevational view of the automobile shown in Fig. 1; and

Fig. 4 is a rear elevational view of the automobile shown in Fig. 1.

The dominant features of my design reside in the body portions shown in solid black lines in the drawings.

I claim:

The ornamental design for an automobile, substantially as shown and described.

HOWARD A. DARRIN.
